WILLIAM V. STAFFORD, OF BROOKLYN, NEW YORK

DESIGN FOR A COMBINED DISPLAY AND FILING CABINET FOR TILE SAMPLES

Application filed March 6, 1929. Serial No. 30,361. Term of patent 14 years.

To all whom it may concern:

Be it known that I, WILLIAM V. STAFFORD, a citizen of the United States, residing in Brooklyn, in the county of Kings and State of New York, have invented a new, original, and ornamental Design for a Combined Display and filing Cabinet for Tile Samples, of which the following is a specification, reference being had to the accompanying drawings, forming part thereof.

Fig. 1 is a front elevation showing my new design for a combined display and filing cabinet for tile samples;

Fig. 2 is a side elevation of the article; and Fig. 3 is a plan view thereof.

I claim:—

The ornamental design for a combined display and filing cabinet for tile samples, as shown.

WILLIAM V. STAFFORD.
